Attorney.

UNITED STATES PATENT OFFICE.

BERTHA M. SCHWAB, OF GOOD GROUND, NEW YORK.

VANITY-CASE.

1,369,938.

Specification of Letters Patent.

Patented Mar. 1, 1921.

Application filed December 6, 1919. Serial No. 343,081.

To all whom it may concern:

Be it known that I, BERTHA M. SCHWAB, a citizen of the United States, residing at Good Ground, Long Island, county of Suffolk, and State of New York, have invented a certain new and useful Vanity-Case, of which the following is a specification.

This invention is a container for toilet preparations of the kind known popularly 10 in the trade as a "vanity case," the same being of small size so as to be carried conveniently in a handbag, pocket, or otherwise about the person.

The case of my invention is equipped 15 with a mirror for the convenience of the user, and according to this invention provision is made, first, for the illumination of the mirror so that it can be used in the dark or at night time, and, second, to so relate 20 the containers for the facial dressings to the mirror that the surface of said mirror remains in a clean polished condition, unsmirched by contact therewith of the facial dressings, particularly the toilet powder.

Accordingly, the case is constructed in 25 two parts or members hingedly connected together, one of said parts being equipped with a mirror and with means for illuminating the same, whereas the other part or 30 member is provided with a compact electric battery and with means for controlling the flow of electric current to said illuminating means. The last mentioned part or member, hereinafter referred to as the body 35 member, is provided, also, with a number of small compartments adapted for containing the required facial dressings, such as rouge, pencils for the eyebrows, etc., and in addition thereto, said body member is pro- 40 vided with a compartment for toilet powder, said compartment being of a desired cubical capacity for the storage of a relatively large amount of toilet powder. In view of the 45 fact that toilet powder when left free will obscure the surface of the mirror, I have constructed the body member in a particular manner to preclude the escape or sifting of such powder into the interior of the case, and to this end, said body member is pro- 50 vided with a compartment the inlet to and outlet from which are positioned exteriorly to the vanity case, preferably at the respective ends thereof.

Other features and advantages of the in- 55 vention will appear from the following de-

scription taken in connection with the drawings, wherein—

Figure 1 is a plan view showing the vanity case in an opened condition.

Fig. 2 is an end view of the case in a 60 closed condition.

Fig. 3 is a cross section in the plane of the dotted line 3—3 of Fig. 1.

Fig. 4 is a longitudinal section on the line 4—4 of Fig. 2.

The case comprises two parts herein 65 shown as a body member A and a cover member B, said parts being hingedly connected in a desirable way as at a in order that the two parts may have a hinged movement on an axis extending lengthwise of 70 said case.

C is a mirror of any suitable construction 75 positioned within the cover member and fixedly attached thereto, said mirror being relatively large so as to afford an adequate area for the view of the face.

A salient feature of my invention consists 80 in the provision of means for illuminating the mirror, whereby the vanity case is adapted for use in the dark or at night time, a condition of use which so far as I am aware is wholly new with me. To these ends, the cover member B is provided with one or more of such illuminating devices, 85 two being shown, one at each side of the mirror. Said cover member is shown as having lamp-sockets d of any suitable form, into which are screwed the base members of incandescent electric lamps D, the whole 90 being in compact relation to the cover member. To attain efficiency, it is preferred to use a reflector E in connection with each lamp, said reflector being concentric with the lamp socket and attached in a suitable 95 manner to the cover member B.

The body member A is shown as being provided with a desirable number of compartments F, G, H for containing the facial dressings. Thus, the compartments F, G 100 are shown as being circular in form and positioned at the respective ends of the body member, whereas the compartment H is of a generally oblong form and positioned at or adjacent to one of the longitudinal side 105 walls of the casing. It is intended that compartments F, G shall contain rouge or other facial dressings, whereas the compartment H receives the pencils used for dressing eyebrows, etc.

110

2

Within the body member A and between the end compartments F G is a space I for the reception of a renewable electric battery J, the latter being of small dimensions and 5 preferably of the kind known as a "dry cell" now so commonly used in the familiar electric torch or flash light. Said electric battery J is retained in position by frictional contact with the body member or the 10 walls of the compartments therein, and said battery is included in circuit with the lamps D, the flow of current being controllable by an appropriate switch j. Suitable means or 15 electrical connections are provided for electrically connecting with the two lamps; as shown, conductors j' lead from the battery to the lamp and from one lamp to the other and from one lamp back to the switch and thence to the battery, or if desired, the battery 20 may be connected in short with the body member. Obviously, the particular manner of connecting the battery with one or both lamps, and for controlling the flow of current, may be modified as desired.

25 In addition to the several compartments herein described and to the battery, the body member A is provided with a longitudinal shallow chamber K, the length and width of which is equal substantially to the dimensions of the body member so as to obtain 30 a chamber of relatively large cubical capacity for the storage of a desirable quantity of toilet powder. Said chamber has no communication, directly or indirectly, with the 35 interior of the vanity case, whereby the toilet powder is precluded from sifting into the case so as to soil or obscure the surfaces of the mirror C or the reflectors E. For filling the compartment K, the body member is provided at one end with a filling nozzle k, 40 slightly protruding beyond the end portion of said member A; said nozzle being desirably closed by a cap K', preferably a screw cap adapted to be removed and replaced at will. A delivery nozzle L is provided at 45 the opposite end portion of the body member, said nozzle being shown as having a perforated plate l and a cap l'. The perforated plate provides means by which the 50 toilet powder may be sifted from chamber K upon a powder puff, a piece of chamois, or other article to be applied to the face as desired; but the escape of powder through the nozzle L is cut off by screwing the cap l' 55 tightly upon the nozzle, whereby the vanity case is adapted to be carried in the pocket or in a handbag without fear of the loss of the powder.

The mode of using my vanity case is 60 readily apparent from the foregoing description taken in connection with the drawings. By opening the cover member, the mirror is fully exposed to afford a view of the face of the user, and should the device 65 be used in the dark or at night, the switch

is operated to close the circuit, whereby current from the battery is adapted to flow into the lamps for lighting them so as to illuminate the mirror, after which the switch is opened for cutting off the illumination. 70

The rouge and pencil compartments are located for free access, and the cap l' can be taken off and the toilet powder sifted upon a puff or chamois and thereafter securely replaced. Of course, the puff or 75 chamois is of such small dimensions that they can easily be carried within and incased by the parts of the vanity case.

Having thus fully described the invention, what I claim as new and desire to secure by Letters Patent is:

1. A vanity case embodying a body member and a cover member hinged for opening and closing movement, said body member being provided with a powder-containing 85 chamber free from communication with the interior of the vanity case and the inlet and the outlet from which chamber are positioned exteriorly to said vanity case, a mirror positioned interiorly of said cover 90 member, and illuminating means carried by said cover member, said mirror and the illuminating means therefor being incased within the vanity case by closing said cover member. 95

2. A vanity case embodying a body member and a cover member hinged for opening and closing movement, said body member being provided with a powder-containing chamber free from communication with the 100 interior of the vanity case and said chamber having a filling inlet and a sifting outlet both positioned exteriorly to said vanity case, a mirror positioned on the inner face of said cover member and adapted to be 105 exposed for service upon opening said cover member, and illuminating means carried by the cover member and positioned adjacent the mirror, said mirror and the illuminating means being foldable with the cover 110 member so as to be incased within the vanity case upon closing the cover member.

3. A vanity case embodying a body member and a cover member hinged for opening and closing movement, a mirror on the 115 inner surface of said cover member whereby the mirror is exposed for service upon opening the cover member, a reflector attached to the cover member on the inner side thereof, said reflector being adjacent said mirror, a 120 light bulb attached to the cover member and positioned in front of the mirror and adjacent said mirror, and electrical means for illuminating the light bulb; said reflector and the light bulb being foldable together with the mirror when the cover member is closed so as to incase the mirror, the reflector and the light bulb within the vanity case. 125

4. A vanity case embodying a body mem- 130

- ber and a cover member connected for opening and closing movement, a mirror on the inner surface of said cover member and adapted to be exposed for service upon 5 opening said cover member, a reflector positioned on the inner surface of the cover member, a light bulb attached to said cover member, and means for feeding current to said light bulb; said light bulb and the reflector being in substantially coaxial relation to each other and in compact relation to the cover member, and said reflector and the light bulb being foldable together with the mirror to lie interiorly of the 10 vanity case upon closing said cover member.
5. A vanity case embodying a body member and a cover member connected for opening and closing movement, said body member being provided with a powder containing chamber free from communication with the interior of the vanity case and said chamber being provided with a filling inlet and with a sifting outlet both positioned ex- 15
- teriorly of said vanity case, a mirror on the inner portion of said cover member, and 20 illuminating means on said cover member, said illuminating means and the mirror being incased within the vanity case upon closing said cover member.
6. A vanity case embodying a body member 25 provided with a hinged cover member, a powder chamber extending longitudinally of the body member substantially from end to end thereof, said powder chamber being closed against communication with said 30 body member and said powder chamber having a filling inlet at one end and a sifting outlet at the opposite end, said filling inlet and the sifting outlet being exteriorly to the body member, and receptacles other 35 than the powder chamber positioned within the body member so as to be accessible freely upon opening the cover member.
- In testimony whereof I have hereunto 40 subscribed my name.

BERTHA M. SCHWAB.
